BIRDHOUSE

Nicholas P. Schur, Cleveland Heights, Ohio

Application July 13, 1949, Serial No. 3,875

Term of patent 3½ years

(Cl. D31—2)

To all whom it may concern:

Be it known that I, Nicholas P. Schur, a citizen of the United States, residing at Cleveland Heights, in the county of Cuyahoga and State of Ohio, have invented a new, original, and ornamental Design for a Birdhouse, of which the following is a specification, reference being had to the accompanying drawing, forming a part thereof.

Fig. 1 is a front elevational view of a birdhouse, showing my new design;

Fig. 2 is a side elevational view thereof; and
Fig. 3 is a perspective view.

I claim:

The ornamental design for a birdhouse, as shown.

NICHOLAS P. SCHUR.
